UNITED STATES PATENT OFFICE.

JOSEPH SCHERER, OF BUFFALO, NEW YORK.

DESIGN FOR A RADIATOR.

SPECIFICATION forming part of Design No. 26,388, dated December 8, 1896.

Application filed October 21, 1896. Serial No. 609,619. Term of patent 3 years.

To all whom it may concern:

Be it known that I, JOSEPH SCHERER, a citizen of the United States, residing at Buffalo, in the county of Erie and State of New York, have invented and produced a new and original Design for a Pin-Radiator Section, of which the following is a specification, reference being had to the accompanying drawings, in which—

10 Figure 1 represents a side elevation of a pin-radiator section. Fig. 2 is a front elevation of a portion of a pin-radiator section, showing the form of the pins, these views being deemed sufficient to fully illustrate my
15 design.

The main feature of my design consists in the rectangular form of the section having a sharp corner 1 at one end of the section and a sharp corner 1^a at the opposite end and side, 20 and at the opposite sides and ends of the sec-

tion the rounded corners 2 and 2^a, formed by a circular rib 3, surrounding the nipple-openings, also a rib 4, entirely surrounding the section. Through the section are two longitudinal openings 5 and 5^a, each surrounded by a 25 rib 6 and 6^a, and its entire surface covered with projecting pins 7. Near one end of the section within the rectangular rib 6 is a small portion 8, provided with two perforations 9 and 9^a, and at the opposite end of the section 30 within the rib 6^a is another small portion 9^a, having two perforations 10 and 10^a.

I claim as my invention—

The design for a pin-radiator section, substantially as herein shown and described.

JOSEPH SCHERER.
